(57) CLAIM

The ornamental design for a signal light for a loading dock with patterns of projected light, as shown and described.

DESCRIPTION

FIG. 1 is a front right top perspective view of a signal light for a loading dock with patterns of projected light showing a first embodiment of our new design;

FIG. 2 is a front right bottom perspective view thereof;
FIG. 3 is a front elevation view thereof, showing a condition of use with a first pattern of light projecting from the signal light for a loading dock;
FIG. 4 is a front elevation view thereof, showing a condition of use with a second pattern of light projecting from the signal light for a loading dock;
FIG. 5 is a right side elevation view thereof, the left side elevation view being a mirror image of the right side elevation view;
FIG. 6 is a top plan view thereof;
FIG. 7 is a bottom plan view thereof;
FIG. 8 is a rear elevation view thereof;
FIG. 9 is a front right top perspective view of a signal light for a loading dock with patterns of projected light showing a second embodiment of our new design;
FIG. 10 is a front right bottom perspective view thereof;
FIG. 11 is a front elevation view thereof, showing a condition of use with a first pattern of light projecting from the signal light for a loading dock;
FIG. 12 is a front elevation view thereof, showing a condition of use with a second pattern of light projecting from the signal light for a loading dock;
FIG. 13 is a right side elevation view thereof, the left side elevation view being a mirror image of the right side elevation view;

FIG. 14 is a top plan view thereof;
FIG. 15 is a bottom plan view thereof;
FIG. 16 is a rear elevation view thereof;
FIG. 17 is a front right top perspective view of a signal light for a loading dock with patterns of projected light showing a third embodiment of our new design;
FIG. 18 is a front right bottom perspective view thereof;
FIG. 19 is a front elevation view thereof, showing a condition of use with a first pattern of light projecting from the signal light for a loading dock;
FIG. 20 is a front elevation view thereof, showing a condition of use with a second pattern of light projecting from the signal light for a loading dock;
FIG. 21 is a right side elevation view thereof, the left side elevation view being a mirror image of the right side elevation view;
FIG. 22 is a top plan view thereof;
FIG. 23 is a bottom plan view thereof; and,
FIG. 24 is a rear elevation view thereof.
The dash-dash broken lines shown in the figures represent portions of the signal light for a loading dock with patterns of projected light that form no part of the claimed design. The dot-dash broken lines shown in the figures define the bounds of the claim design and form no part thereof.
